PATENTED DEC. 25, 1906.

E. H. WARREN.

COMBINED CAR AND AIR BRAKE COUPLING.

APPLICATION FILED JUNE 28, 1906.

UNITED STATES PATENT OFFICE.

EDWARD H. WARREN, OF RENTIESVILLE, INDIAN TERRITORY, ASSIGNOR
OF ONE-HALF TO GEORGE FIELDS, OF RENTIESVILLE, INDIAN TERRI-
TORY.

COMBINED CAR AND AIR-BRAKE COUPLING.

No. 839,682.

Specification of Letters Patent.

Patented Dec. 25, 1906.

Application filed June 28, 1906. Serial No. 323,897.

To all whom it may concern:

Be it known that I, EDWARD H. WARREN, a citizen of the United States, residing at Rentiesville, in District 10, Indian Territory, have invented a new and useful Combined Car and Air-Brake Coupling, of which the following is a specification.

This invention relates to combined car and air-brake couplings, and has for its object to provide means whereby the coupling of the draw-heads will automatically effect the union of the train-pipe couplings of adjacent cars.

A further object of the invention is to provide a coupler having a laterally-movable jaw provided with guiding-flanges, whereby when the cars are coupled the flanges will interengage and force the jaws to closed or operative position.

20 A further object is to provide the coupler with a locking member adapted to automatically engage the shank of the movable jaw for locking the same in engagement with the mating jaw of an adjacent coupler when the union of said couplers is effected.

A further object is to provide improved means for automatically opening and closing the valve or stop-cock of the train-pipe as the cars are coupled and uncoupled.

30 A still further object of the invention is to generally improve this class of devices so as to increase their utility, durability, and efficiency, as well as to reduce the cost of manufacture.

35 With these and other objects in view the invention consists in the construction and novel combination and arrangement of parts hereinafter fully described, and illustrated in the accompanying drawings, it being understood that various changes in form, proportions, and minor details of construction may be resorted to within the scope of the appended claims.

In the accompanying drawings, forming a part of this specification, Figure 1 is a top plan view of a combined car and air-brake coupler constructed in accordance with my invention, showing the pivoted jaws in operative position. Fig. 2 is a similar view showing the draw-heads uncoupled. Fig. 3 is a longitudinal sectional view of one of the draw-heads, showing in dotted lines the fluid-pressure valve in open position and in full lines in closed position. Fig. 4 is a ver-

tical sectional view taken on the line 4-4 of Fig. 1. Fig. 5 is an end view of one of the draw-heads. Fig. 6 is a perspective view of the locking member detached.

Similar numerals of reference indicate corresponding parts in all of the figures of the drawings.

The improved coupler comprises a draw-head 5, preferably rectangular in shape and provided on one side thereof with a longitudinal slot or recess 6, as shown. Pivoted 65 mounted on the draw-head 5, as indicated at 7, is a movable jaw 8, provided with a reduced shank 9; the free end of which is seated within the opening 6 and is inclined or beveled, as indicated at 10, for the purpose hereinafter referred to.

The free end of the pivoted jaw is provided with a shoulder 11, defining a lateral projection 12, having a semicircular opening 13 formed therein and adapted to register with 75 a corresponding opening formed in the free end of the movable jaw of the adjacent draw-head when said draw-heads are coupled. The pivoted jaw 12 of each draw-head is provided with oppositely-disposed guide-flanges 14, 80 the active faces of which are inclined or beveled, as indicated at 15, for engagement with the correspondingly-inclined faces of similar guide-flanges 16, secured to or formed integral with the draw-heads, as shown, so that 85 when the draw-heads are coupled the guide-flanges will interengage, and thus force the pivoted jaws to closed or operative position.

Communicating with the longitudinal recess 6 of each coupler is a vertical recess 17, 90 in which is mounted for sliding movement a wedge-shaped locking member 18, adapted to engage the inclined face of the shank 9 when the jaws are in closed position and lock the same against lateral movement. The 95 locking members 18 normally rest on the reduced shanks 9 of the pivoted jaws 8, so that when the free ends of the jaws are forced inwardly by engagement with the guiding-flanges said locking members will drop by 100 gravity to operative position, between the inclined faces of the shanks 9 and the adjacent walls of the shank. As a means for elevating the locking members to permit uncoupling of the cars there is provided a suitable crank-shaft 19, one end of which is connected to the locking member through the medium of a chain 20, while the opposite end

thereof extends laterally beyond the side of the car and is provided with a suitable operating-handle, by means of which the shaft may be rotated to elevate the locking member, and 5 thus release the pivoted jaw.

The draw-heads 5 are each provided with a longitudinal opening 21, in which is seated a fluid-pressure pipe 22, said pipe being connected through the medium of a branch pipe 23 with a train-pipe 24. The fluid-pressure pipe 22 is mounted for longitudinal movement in the slot 21 and the branch pipe 23 extends through an opening 25, communicating with the slot 21, thereby to permit a corresponding longitudinal movement of the branch pipe when the cars are coupled. The inner end of the pipe 22 is connected to a cross-bar 26, seated in a transverse opening 27, formed in the rear end of the draw-head, 10 said bar by engagement with the walls of the recess serving to limit the longitudinal movement of the fluid-pressure pipe. The outer or free end of the pipe 22 is provided with an enlarged head 28, in which is seated a gasket 29, 15 adapted to engage the corresponding gasket on the fluid-pressure pipe of the adjacent draw-head, so as to permit the free passage of air from one pipe to another. The head 28 is formed with an annular shoulder 30, and 20 interposed between said shoulder and a similar shoulder 31, formed in the draw-head 5, is a coil-spring 32, the normal tendency of 25 which is to exert an outward pressure on the head of the pipe 22, with the branch pipe 23 disposed adjacent the front wall of the slot 25.

The passage of air to the pipe 22 is controlled by a stop cock or valve 33, having secured thereto and mounted for movement therewith a segmental rack 34, the teeth of 30 which mesh with the teeth of the eccentric 35. The eccentric 35 is pivotally mounted in a stationary hanger 36, depending from the adjacent draw-head 5, and rigidly secured to said hanger and retained in position 35 by the pivot-pin 37 is a yoke 38, which embraces the rack 34 and serves to normally hold the latter in engagement with the teeth on the eccentric. The eccentric 35 is preferably weighted, so that the teeth on the eccentric will be held in engagement with the teeth on the lever 34 when the latter is in upright position and assist in elevating the free end of said lever when the latter is in lowered position, and the cars uncoupled, as best 40 shown in Fig. 3 of the drawings. It will thus be seen that as the cars are coupled the pipe 22 will move longitudinally of the draw-head, which causes the rack 34 to engage and rotate the cam or eccentric 35 to the dotted-line position shown in Fig. 3 of the drawings, 45 thus depressing the lever 34 and opening the valve 33, so that the air from the train-pipe 24 is free to flow through the fluid-pressure pipe of one draw-head to the adjacent draw-head.

When the cars are uncoupled, the spring 32 will force the pipe 22 outwardly, thus causing the teeth on the rack to rotate the member 35, which latter being weighted and eccentrically mounted in the hanger 36 will 50 elevate the rack to the full-line position shown in Fig. 3 of the drawings, thereby closing the valve and cutting off communication between the train-pipe and fluid-pressure pipe 22.

The yoke 38 is preferably disposed at an angle to the longitudinal plane of the hanger 36 and is so arranged as to permit free movement of the rack within the yoke when the cars are coupled and uncoupled without liability of the teeth on the rack becoming disengaged from the teeth on the eccentric.

From the foregoing description it is thought that the construction and operation of the device will be readily understood by those skilled in the art, and further description thereof is deemed unnecessary.

Having thus described the invention, what is claimed is—

1. The combination with a draw-head having a fluid-passage, a valve controlling said passage and provided with operating means and an eccentric engaging the operating means for moving the valve to open and closed position as the draw-heads are coupled 90 and uncoupled.

2. The combination with a draw-head having a fluid-pressure pipe mounted for longitudinal movement therein, a valve, and an eccentric adapted to engage the valve and 100 actuated by the movement of the fluid-pressure pipe for opening and closing said valve.

3. The combination with a draw-head having a fluid-pressure pipe mounted for longitudinal movement therein, a branch pipe 105 communicating with the fluid-pressure pipe, a valve having an operating-lever secured thereto, and an eccentric operable by the movement of the fluid-pressure pipe and adapted to engage the lug for opening and 110 closing the valve.

4. The combination with a draw-head having a fluid-pressure pipe mounted for longitudinal movement therein, and provided with a depending branch pipe communicating with said fluid-pressure pipe, a valve having a rack operatively connected therewith, and a toothed cam engaging the rack for moving the valve to open and closed position.

5. The combination with a draw-head having a fluid-pressure pipe mounted for longitudinal movement therein, a branch pipe provided with a valve, a hanger depending from the draw-head, and an eccentric pivotally mounted in the hanger and adapted to engage the valve for moving the latter to open and closed position.

6. The combination with a draw-head having a fluid-pressure pipe mounted for longi-

tudinal movement therein, a branch pipe depending from the fluid-pressure pipe and provided with a valve, a lever operatively connected with the valve, an eccentric engaging the lever for moving the valve to open and closed position, and a yoke embracing the eccentric and lever, respectively.

7. The combination with a draw-head having a fluid-pressure pipe mounted for longitudinal movement therein, a branch pipe communicating with the fluid-pressure pipe and provided with a valve, a segmental rack operatively connected with the valve, a hanger depending from the draw-head, and an eccentric pivotally mounted in the hanger and provided with peripheral teeth adapted to engage the teeth on the rack for moving the valve to open and closed position.

8. The combination with a draw-head provided with intersecting longitudinal and vertical slots, and having a fluid-pressure pipe mounted for longitudinal movement therein,

a movable jaw pivotally mounted for lateral movement on the draw-head and provided with a reduced shank seated in the longitudinal slot, a wedge-shaped locking member mounted in the vertical slot and adapted to engage the shank of the jaw for locking the same in closed position, a branch pipe communicating with the fluid-pressure pipe and provided with a valve, a segmental rack operatively connected with the valve, and an eccentric provided with peripheral teeth adapted to engage the teeth of the rack for moving the valve to open and closed position when the draw-heads are coupled.

In testimony that I claim the foregoing as my own I have hereto affixed my signature in the presence of two witnesses.

EDWARD HENRY WARREN.
